(57) **CLAIM**

The ornamental design for a security base station as shown and described.

DESCRIPTION

FIG. 1 is a top and front perspective view of a security base station showing my new design;

FIG. 2 is a top and rear perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is another top and rear perspective view thereof;

FIG. 10 is another top and front perspective view thereof;

FIG. 11 is a bottom, rear and right side perspective view thereof; and,

FIG. 12 is an enlarged view of portion 12 in FIG. 1.

The broken lines in the drawings illustrate portions of the security base station which form no part of the claimed design.

1 Claim, 12 Drawing Sheets
